UNITED STATES PATENT OFFICE.

SIGMUND SCHLESINGER, OF NEW YORK, N. Y.

COMBINED WATCH AND UMBRELLA-HANDLE.

Specification of Letters Patent. Patented July 13, 1915.

1,146,351.

Application filed September 1, 1914. Serial No. 859,616.

To all whom it may concern:

Be it known that I, SIGMUND SCHLESINGER, a citizen of the United States, and a resident of New York city, borough of Brooklyn, in the county of Kings and State of New York, have invented certain new and useful Improvements in Combined Watches and Umbrella-Handles, of which the following is a specification.

The object of my invention is to provide an umbrella handle with a watch carried thereby, and means to permit the watch winding-member to be retained, when not being used, substantially within the handle, so as not to be injured and yet to permit said member to be moved outwardly into position for use in winding or setting the watch.

My invention comprises novel details of improvement and combinations of parts that will be more fully hereinafter set forth and then pointed out in the claims.

Reference is to be had to the accompanying drawings forming part hereof, wherein Figure 1 is a face view of a portion of an umbrella handle embodying my invention; Fig. 2 is a section on the line 2, 2, in Fig. 1; Fig. 3 is a partly broken enlarged detail of Fig. 1, and Fig. 4 is a sectional detail showing the winding member folded into the handle.

Similar numerals of reference indicate corresponding parts in the several views.

The numeral 1 indicates a support, such as the handle of an umbrella or other analogous article, which is provided with a socket 2, shown in one face of the handle, within which socket the watch movement 3 is located. To retain the movement in place I have shown a frame or casing 4 set into socket 2, and retained therein by one or more screws 5, which frame or casing is adapted to receive the movement 3, and said frame is provided with an opening 4^a through which the threaded stem 3^a of the watch movement is adapted to pass.

At 6 is a rim or bezel carrying the glass crystal 7 of the watch movement, and shown having a flange 6^a adapted to enter the enlarged portion 2^a of socket 2 and to snap on the outer edge portion of frame or casing 4, whereby the watch movement is retained upon the handle. The handle 1 is provided with a bore 8 communicating with socket 2, into which bore the stem 3^a projects, and in which bore the rotative winding member 9

is located. The member 9 has internal threads 9^a receiving the threads of the watch stem 3^a, whereby when the member 9 is fitted, as shown in Figs. 2 and 3, and is rotated the watch may be wound, and when member 9 is pulled outwardly the hands of the watch may be set. The member 9 has a handle member 9^b which is pivoted to part 9, as upon the pivot 10, so that the handle member 9^b may be folded down into the recess 11 shown in the end of the handle 1 (Fig. 4), and may be raised up into position for winding and setting the watch as in Figs. 1, 2 and 3.

The parts are so arranged that the winding member 9, 9^b is substantially concealed within the handle, when not in use, so as to prevent injury to the winding member. To this end the outer part of member 9 is slotted at 9^c, and the shank portion of the part 9^b is adapted to pass in and out of such slot as part 9^b is swung up and down, thereby permitting the part 9^b to be readily concealed within recess 11 against injury. To retain the part 9^b in the closed position within the recess 11, or in the open position for use, I provide spring-means which, in the example illustrated, comprises a spring 12, shown located within a bore 9^d in member 9 and bearing at the inner end against said member and at the outer end against a plug or the like 14 that bears against the squared or flattened end or side portion of the shank of member 9^b. By this means the member 9^b will be prevented from spontaneously opening, and will be retained in firm position when opened for use for winding the watch or setting its hands.

While I have described the watch and its winding member as applied upon an umbrella handle, it will be understood that the watch may be similarly applied to any desired article of personal use, and by the term "handle" as used herein I mean a support such as an umbrella handle or article of personal use referred to.

Having now described my invention what I claim is:

1. The combination of a handle having a bore therein, a watch movement having a stem, and means to retain the watch movement within the handle, with a winding member comprising a plurality of parts, one of said parts being attached to said watch stem and journaled within said bore in the handle, the watch stem being rotative in

- 5 said bore, and the other part being pivotally connected with the first named part and adapted to fold relatively thereto, said handle having a surface recess surrounding the first named part of the winding stem and also offset therefrom to receive the second named part of said winding member when folded toward the handle to protect and conceal the winding member.
- 10 2. The combination of a handle, with a watch movement having a threaded stem, means to retain said movement within the handle, and a winding member comprising two parts pivotally connected together, one of said parts having a threaded portion receiving said threaded stem of the watch movement and journaled within a bore in the handle, said part of the winding member having a bore without said stem, and a spring within said bore having a bearing at the inner part of said member and adapted to coact with the other part of said winding member to retain the latter in different positions, the handle having countersunk means to receive and protect the pivotal part of the winding member.
- 15
- 20
- 25

3. The combination of a handle having a socket in one side, a frame within said socket, and provided with an opening, a watch movement within said frame and provided with a stem, means to retain said movement within said frame with said stem projected through said opening, said handle having a bore receiving said stem, a winding member journaled in said bore, and means to operatively connect the winding member with the watch stem, said winding member having a pivotal finger-piece adapted to project outwardly in position to be operated, said handle having a surface recess surrounding the winding member adapted to receive said finger piece when folded in the inoperative position to protect and conceal the latter.

Signed at New York city, in the county of New York, and State of New York, this 31st day of August A. D. 1914.

SIGMUND SCHLESINGER.
